(57) **CLAIM**

The ornamental design for a quick engage/release clamp device, as illustrated and described.

DESCRIPTION

FIG. 1 is a perspective view illustrating the quick engage/release clamp device in engaged condition;
FIG. 2 is a front elevational view thereof;
FIG. 3 is a left side elevational view thereof;
FIG. 4 is a right side elevational view thereof;
FIG. 5 is a rear elevational view thereof;
FIG. 6 is a top plan view thereof;
FIG. 7 is a bottom plan view thereof; and,
FIG. 8 is a perspective view thereof showing the clamp device in released and open condition.
